UNITED STATES PATENT OFFICE.

FRANK H. WHITNEY, OF FRIENDSHIP, MAINE.

BENCH-STOP.

SPECIFICATION forming part of Letters Patent No. 329,795, dated November 3, 1885.

Application filed May 5, 1885. Serial No. 161,439. (No model.)

To all whom it may concern:

Be it known that I, FRANK H. WHITNEY, a citizen of the United States, residing at Friendship, in the county of Knox and State 5 of Maine, have invented certain new and useful Improvements in Bench-Stops, of which the following is a specification, reference being had to the accompanying drawings.

This invention has relation to bench-stops, my object being to provide a stop which shall be so constructed as to be perfectly rigid, and yet at the same time be capable of adjustment for holding in place work of varied thicknesses; and the invention consists in certain 15 novel features of construction hereinafter specified, and particularly pointed out in the claims.

Referring to the drawings, Figure 1 is a plan view of my stop; Fig. 2, a side elevation; 20 Fig. 3, a central longitudinal section, and Fig. 4 a detail in perspective hereinafter referred to.

Like letters indicate like parts in all the figures.

25 A represents a bench; A', a cylindrical aperture therein, into which a solid and, preferably, cylindrical metal plug, B, is tightly driven. Set into the upper end of the plug, flush with the surface thereof, is a spring 30 tongue or plate, C, which is secured with a recess, B', by means of a screw, C'. At the other end of the tongue or plate C is formed a head, C², the end of which is provided with teeth or serrations C³. From the aperture A', 35 and extending parallel to the tongue or plate C, is a recess, A², which terminates in an aperture, A³, passing entirely through the bench. Upon the under side of the tongue or plate C is secured, by rivets or otherwise, an arm, D, 40 which is bent, as at D', and provided with a bifurcation, D², all as clearly shown in Fig. 4. The bench or table A is recessed at both sides of the aperture A³, to form shoulders A⁴, within which is a plate, E, set in flush there- 45 with, and secured thereto by screws E'. The plate E is provided at its center with a screw-threaded aperture, E², through which is adapted to pass a thumb-screw, F, near the top of which is formed an annular groove, F', which 50 forms a bearing for and is embraced by the bifurcations D² of the arm or plate D.

This being the construction, the operation is as follows: By means of the thumb-screw F the plate C, by reason of its connection with the arm D, which has a bearing in the annular groove F' of said screw, will be elevated or lowered, and remain in that position when thus adjusted, thus presenting the teeth C³ at the desired height for different kinds of work, and that the plate can, by reason of the recess A², be drawn down flush with the upper surface of the bench. Furthermore, that all dust, dirt, and shavings that drop into the aperture A³ will fall through the same to the floor, as the plate E does not close the aperture entirely, but is merely wide enough to give the requisite strength. By the use of the solid plug B, which is also of metal, and which has a driving fit with the bench, and by reason of the metallic spring-plate C being seated within a recess in said plug, I secure a solid bearing or stop having a large bearing surface, and one which will not weaken or become loose by frequent or hard use. By driving the plug B upward and turning 75 up the screw F the entire stop can be adjusted for very thick wood.

It is very evident that minor details of construction may be changed, and I do not limit my invention to the exact construction, but 80 reserve my right to make such alterations as may suggest themselves to persons skilled in the art to which my invention appertains.

Having described my invention and its operation, what I claim is—

1. In a bench-stop, the combination of a plug for insertion into a base or bench-top, a metallic plate secured to the plug, and any well-known devices arranged near the free end of the plate for raising and lowering the free 90 end of said plate, substantially as specified.

2. In a bench-stop, and in combination with a bench provided with apertures, a plug adapted to fit one of said apertures, a spring plate secured to said plug, a bifurcated arm secured 95 to the under side of the free end of said plate, and raising and lowering devices connected with said arm and with the bench, substantially as specified.

3. A bench-stop consisting of a plug, a 100 spring-plate secured to the same, a bifurcated arm secured to the free end of said spring-

plate, and a thumb-screw passing upwardly through the bench and engaging with said bifurcated arm, substantially as specified.

4. The combination of the bench A, having the recess A², the apertures A' A³, and the plug B, spring-plate C, secured thereto, plate E, and thumb-screw F, substantially as specified.

5. The combination of the bench A, having recess A² and apertures A' A³, with the plug B, having recess B', spring-plate C, secured to the plug in said recess, and thumb-screw F, mounted in plate E, substantially as shown and described.

6. The combination of the bench A, having

recess A² and apertures A' A³, with the plug B, fitted in recess A', and having recess B', spring-plate C, seated in said recess B', and secured therein by the screw C', arm D, having the bifurcations D², thumb-screw F, having the annular groove F', embraced by said bifurcations, and plate E, substantially as shown and described.

In testimony whereof I affix my signature in presence of two witnesses.

FRANK H. WHITNEY.
